UNITED STATES PATENT OFFICE.

HAROLD ROWNTREE, OF CHICAGO, ILLINOIS.

CAR SIGNALING DEVICE.

1,134,640.

Specification of Letters Patent.

Patented Apr. 6, 1915.

Application filed May 22, 1911. Serial No. 628,668.

To all whom it may concern:

Be it known that I, HAROLD ROWNTREE, a citizen of the United States, residing at Chicago, county of Cook, State of Illinois, 5 have made a certain new and useful Invention in Car Signaling Devices, of which the following is a specification.

This invention relates to car signaling devices, and particularly to devices for signaling to a street car motorman to indicate 10 when it is safe to start the car.

The object of the invention is to provide a signaling device, which is simple and efficient, for indicating to the motorman at 15 the front end of the street car when it is safe for the car to be started.

A further object of the invention is to provide a signaling device of the character referred to which is controlled automatically by the closing movement of the door employed to control the entrance and exit 20 of passengers to and from the car, thereby indicating to the motorman whether or not the door is closed and it is safe to start the 25 car.

A further object of the invention is to provide a signaling device of the character referred to which utilizes a portion only of the closing movement of the door to effect 30 the operation of the signal device, thereby leaving the device inoperative when the door is completely closed.

Other objects of the invention will appear more fully hereinafter.

The invention consists substantially in the combination, construction, location and relative arrangement of parts, all as will be more fully hereinafter set forth, as shown in the accompanying drawings, and finally 40 pointed out in the appended claims.

Referring to the accompanying drawings:—Figure 1 is a view showing the application of a signaling device embodying my invention in connection with a sliding door. Fig. 2 is a similar view showing the application of a signaling device to a swing- 45 ing or folding door.

In the practical operation of street cars accidents frequently happen by reason of 50 the conductor from the rear platform giving the motorman at the front end of the car the starting signal for starting the car while passengers are boarding or alighting from the car or attempting to do so. This 55 source of danger is largely avoided by pro-

viding the rear platform of the car with side doors which are opened only when the car stops to take on or to let off passengers. But even with cars having platform side doors it sometimes happens that the conductor gives 60 the starting signal to the motorman too soon, and while passengers are still attempting to get on or off the car, and before the doors controlling the entrance and exit doorways are completely closed.

It is among the special purposes of my present invention to provide an automatic signaling device, which is controlled by the closing movement of the door on the rear platform, for giving the motorman at the 70 front end of the car the starting signal.

In carrying out my invention I propose to employ a portion only of the closing movements of the door, to effect the control and operation of the signaling device, and, preferably, I propose to utilize the closing movement of the door as it approaches its final closed position for effecting the operation and control of the signal device, so that by the time the door reaches its completely 75 closed position the starting signal will have been given and the signaling apparatus thrown out of operation.

In Fig. 1, I have shown my invention as applied to a sliding door. In this view of the drawing, A, designates the sliding door suspended by hangers or rollers B, from a track C, in the usual or ordinary manner. The signal device is shown in this instance in the form of an electrically operated bell 80 D, located at the front or motorman's end of the car, though I wish it to be understood that my invention, as defined in the claims, is not to be limited or restricted to an electrically operated signaling device as other 85 forms of signaling device are equally well adapted for use in carrying out my invention. The circuit of the electrically operated signal device is supplied with current from a battery or other source of current indicated at E. Arranged in the circuit of the battery is a fixed contact 10, to which the 90 battery terminal wire a, is connected.

Mounted adjacent to the contact 10, is a contact arm 11, pivoted at 12, and having a heel extension 13, arranged in the path of travel of a lug 14, connected to move with the door A, so that as the door slides in one direction or the other the projection 14, engages the heel 13, of pivoted arm 11 and rocks said 100 105 110

arm in one direction or the other according to the direction of movement of the door. The arm 11, is acted upon by a spring 14, or other convenient retracting means, tending to yieldingly maintain said arm 11, in a normal position out of bearing relation with respect to contact 10. In the particular arrangement shown, to which, however, in its broadest scope, my invention, as defined in the claims, is not to be limited or restricted, a lever 15, pivoted at one end as at 16, has its free end arranged to engage studs or pins 17, on the arm 11, the spring 14 acting on the lever 15. From this arrangement it will be seen that the spring 14, is placed under compression whether the arm 11, is rocked in one direction or the other, and said spring constantly tends to return the arm 11, to normal position whatever may be the direction in which said arm is rocked by the movement of the door. The contact 10, is placed at one side of the arm 11, so that circuit connection is made therewith only when said arm is rocked in one direction. The rocking movement of said arm in the opposite direction being merely an idle movement. In the relation of the parts shown in Fig. 1 the door A is closed. If now the door is moved toward the left from its closed position the projection 14 will strike the heel 13 of arm 11, as it passes by the same, thereby rocking the arm 11 in a direction away from contact 10. This is the idle movement referred to. As the door continues on its opening travel the projection 14, passes by the heel 13, thereby permitting the spring 14, to restore the arm 11 to normal position. When the door is shifted or moved in the opposite direction however, that is, toward closed position, the projection 14 will engage heel 13, on the left hand side thereof, as said projection passes said heel, and as the door approaches its closed position, thereby rocking the arm 11, in a direction to engage contact 10, momentarily or until the door in its closing travel carries the projection 14, past the heel. When the disengagement of projection 14, with heel 13, takes place, the arm 11, is restored to normal position thereby breaking its connection with contact 10. The contact arm 11, is in electrical connection with the signal device through battery terminal wire b so that when the said arm bears upon contact 10, circuit is completed from the battery through the signal device thereby giving the signal to the motorman. The completion of this circuit however, is momentary, as the door approaches its closed position, and is broken by the time the door reaches its completely closed position.

If desired and in order to give two separate signals, this being the standard "ahead" signal for motorman, two contacts 10 and coöperating arms 11, may be em-

ployed and located in close proximity to each other and adapted to be operated successively during the closing movements of the door so as to give the two rings or actions to the signal device.

In the foregoing description I have shown my invention as applied to a sliding door. It is obvious that my invention is equally well adapted for application to a folding, swinging or other form of door and in Fig. 2, I have shown application thereof to a folding door of a common type. In this view the door is indicated at F, and in this instance is composed of folding sections operated by vertical shafts G placed at opposite sides of the doorway. In the application of my invention to this type of door an arm H, is mounted upon one of the door operating shafts G, to rock or move therewith, said arm having a pin J, corresponding in purpose and function to the projection 14, above described with reference to the sliding door in that said pin coöperates with the heel portions 13, of the contact arms 11, the latter coöperating with contacts 10, arranged in the circuit terminals of the signal device D, and its source of current E, and whether one or two of such circuit controlling or contact devices be employed, that is, whether one or two signals are to be given. The operation of the signal controlling mechanism, and the construction thereof, are identical in every respect with that above described with reference to Fig. 1.

From the foregoing description it will be seen that I provide an exceedingly simple automatic door signal for either sliding, folding, swinging, or other form of doors, and in which during the opening movements of the doors no signal is given but in the closing movement a signal is given to the motorman, the operation of the signal device being accomplished during a part only of the closing movement, but the arrangement is such that when the door is fully closed the signal apparatus is again put in its normal out-of-commission condition. It will also be seen that one or two separate successive operations of the signal may be effected by employing one or two signal controlling connections as above explained.

It may sometimes be desirable to operate the signal during the movements of the door in opening as well as in closing. This exigency might arise in the case where the conductor might for some cause open the door during a temporary halt of the car at a point other than a usual stopping point, unless the motorman is informed in some manner that the door is open he is liable to start up the car when the cause of its temporary stoppage is removed while the door is still open. In such and other cases it is desirable to inform the motorman whenever the door is opened without depending on the con- 125 129

tor. This may be accomplished in a very simple manner in my invention, by simply causing the opening movement of the door as well as the closing movement thereof to operate the signal device. In the particular embodiment shown, this operation may be effected by simply adding an extra contact to one or both of the signal controlling devices, as indicated in dotted lines at 20, Fig. 2, and connect the same in circuit with the battery terminal *a*. I prefer to actuate the signal device only once during the opening movement of the door as that is the standard "stop" signal to the motorman. In the arrangement shown the contact 20 is placed on the opposite side of lever 11 from contact 10, so that as the door opens one operation of the signal is effected and in closing two operations of the signal is effected thus giving both the normal stopping and the normal starting signals to the motorman by the mere act of operating the doors.

It is obvious that the signal device may be operated from any suitable or convenient part connected to move coincidently with the door.

Having now set forth the object and nature of my invention, what I claim as new and useful, and of my own invention, and desire to secure by Letters Patent of the United States is:—

1. In a signaling mechanism for cars, a signal device located at the front end of the car, a plurality of means for controlling the same, a door located at the rear end of the car and adapted to open and close and means carried by the door to move therewith past said controlling means and operating to successively actuate said controlling

means during a portion of the movement of the door.

2. In a signaling mechanism for cars, a signal device located at the front end of the car, a circuit therefor, a plurality of switches for controlling said circuit, a door located at the rear end of the car and means carried by the door to move therewith and operating past said switches for successively operating said switches during portions of the closing movement of the door.

3. In a signaling mechanism for cars, a signal device, independent controlling devices therefor, a door, means carried by said door to move past said controlling devices when the door is moved to engage the same, and operating to actuate the signal once during the opening movement of the door and a plurality of times during the closing movement of the door.

4. In a signaling mechanism for cars, a signal device, independent controlling devices therefor, a door and means carried thereby and moving past said controlling devices when the door is moved, one of said controlling devices being operated to actuate the signal during the opening movement of the door, and both actuating the same successively during the closing movement of the door.

In testimony whereof I have hereunto set my hand in the presence of the subscribing witnesses, on this 1st day of May A. D., 1911.

HAROLD ROWNTREE.
